Nelson W. Howard

UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

SUPPLYING APPARATUS.

Application filed January 5, 1927. Serial No. 159,115.

The present invention relates to apparatus for supplying nails or other fastenings. It is particularly designed for furnishing nails for such work as the attaching of 5 heels.

For purposes of the character above indicated, a successful apparatus is that disclosed in Letters Patent of the United States No. 1,325,751, Pope, December 23, 10 1919. In this, a block, holding in vertical openings each containing a nail, a plurality of loads or sets of nails, is fed in successive steps to deliver these nails to the loading mechanism of a heel-attaching machine, said 15 block being replaced by another when the nails are exhausted. Under some conditions, as when a heeling operator is very rapid, it is found that the act of shifting the blocks occupies a substantial portion of 20 his time, this markedly decreasing his efficiency. An object of this invention is to increase the holding capacity of such supplying apparatus, without materially increasing its cost and without adding to the 25 burden of the operator in effecting the delivery of the fastenings.

I attain this end by the employment of a holder, in which the fastenings, ordinarily 30 nails, are disposed in a plurality of series preferably arranged in sets, with which co- 35 operates means which delivers and counts such deliveries from a set, together with means controlled by the counting means for preparing another set for delivery. When 40 this invention is applied to the nail-block of the previously mentioned patent, it will be seen that the capacity of the system may be increased to whatever extent it is feasible to lengthen the series. I prefer to arrange 45 the series vertically, the nails standing end upon end, there being a plurality of these series, furnishing the previously mentioned set, containing a load of nails for the machine supplied. The delivery from 50 all the series of each set is simultaneously controlled. The delivery from the entire series in the set having been made, another set is brought into delivering position, without attention on the part of the operator. 55 As shown herein, the passages in the holder in which the series of nails are contained, and which may be furnished by tubes secured in openings in top and bottom plates, 60 have co-operating with them a controlling

member, in the form of a detent, provided 55 with portions alternately contacting with the terminal nails of the series. This controlling member, if desired, may be common to a set of the series of nails, it having nail-engaging portions corresponding to 60 each series. To bring about the delivery of the nails most effectively, I utilize the device or loader which transfers them to the heeler or other machine. This may not only actuate the controlling member by 65 which successive delivery of the load of nails from one or more series is made, but may also bring other series to delivering position. I have shown the loader, when in nail-receiving position, as operating the nail-controlling detent member and rotating an operation-counting ratchet-wheel. The latter, after a number of steps corresponding to the nails in a series, may, through a contact member or cam which it governs, operate ratchet mechanism advancing a carriage or holder-support over a plate through 70 openings in which successive loads of nails are delivered.

One of several possible embodiments of 80 this invention is illustrated in the accompanying drawing, in which

Fig. 1 is a broken side elevation of my improved supplying apparatus;

Fig. 2, a broken end elevation looking 85 from the left in Fig. 1; and

Fig. 3, a perspective view of a portion of the detent mechanism.

A supporting bracket 10 is adapted to be attached to the frame of a heeling machine, 90 and has mounted upon it, upon standards 12, the bed-plate 14 of the patented machine, of which mention has been made. Depending from the plate is a tube-holding frame or mug 16, the tubes 18 of which lead from a 95 transverse series of delivering openings 20 in the bed-plate to a foot-plate 22, where they are arranged in accordance with the nailing design to be employed. Movable in horizontal ways at the opposite or upper side of the plate 14 is a carriage 24 adapted to support a nail-holder or magazine. This holder is shown as consisting of relatively thin blocks or plates 26 and 28, spaced from each other and containing transverse sets 100 of openings, each equal in number to the maximum load of nails to be delivered. These sets of openings extend in parallel

lines from one extremity of the plates to the other. In both plates, the openings are similarly arranged so they are in vertically alined pairs, which are joined by tubes 30 secured at each end in the respective plate-openings. The diameter of each tube is such that it is adapted to hold a vertical series of nails N resting end upon end. As many as twelve nails may be held in each tube, being 10 temporarily retained in place by a plate 32, upon which the point of the bottom nail rests. This plate has inturned ends 34 entering grooves in the opposite edges of the plate 26, and may thus be slid longitudinally 15 thereof to free the openings of the holder-passages. The holder is advanced step by step over the plate 14 by ratchet mechanism, which may include a series of teeth 36 carried by the plate, with which teeth co-operates a pawl 38 pivoted on a lever 40 fulcrumed at 42 on a bracket 43 secured to 20 one of the standards 12.

As the above-described ratchet mechanism is operated, in a manner which will later be 25 described, the transverse sets of holder-passages are successively brought through the travel of the holder into registration with the plate-openings 20. As the series of nails descend by gravity in the passages, the terminal nail in each strikes the lower projection 44 of a controlling detent 46, and with the entire series is temporarily held thereby. The detent appears as a bar mounted beneath the plate to oscillate about pivots 48, and may be common to the entire set of passages, having a plurality of the projections 44 spaced from one another. Above these is 30 a similarly arranged series of projections 50. In the oscillation of the bar upon its pivots, the projections 44 and 50 are alternately carried into nail-retaining position, and withdrawn to releasing position through slots 52 in the upper sections of the mug-tubes 18. After each projection 44 has freed the terminal nail of the series so that it falls through 35 the corresponding tube 18, the associated projection 50 contacts and retains the succeeding nail, which now terminates the series. In this way, delivery of the nails one by one is effected with certainty.

Mounted to swing upon the frame of the heelng machine is a device by which the nails are transferred from the supplying apparatus to the inserting mechanism of the machine. Herein it appears in the form of the well-known loader-arm 54, the nail-receiving block of which contains openings which may be brought into registration with the openings in the foot-plate, in which the tubes 18 terminate. In this receiving position, a cam-incline 56 upon the loader-arm contacts with a roll 58 rotatable upon the lower end of a rod 59 depending from an arm 60 upon the double detent 46. This rod 65 is guided in the bracket 43, and is held nor-

mally down into the path of the incline 56 of the loader by a spring 64 surrounding the rod and located between the bracket and a collar 66 secured to the rod. As the openings of the loader-block move into alignment with the foot-plate-openings, the incline 56 raises the rod 59 sufficiently to produce the oscillation of the detent 46, resulting in the release by the projections 44 of the entire set of terminal nails from the series in 70 the holder-passages alined with the plate-openings 20 and the engagement of the succeeding nails by the projections 50. When the loader-arm is swung in the reverse direction to transfer the nails to the die-block of 75 the heeler, the release of the rod 59 by the cam-incline allows the spring 64 to restore the detent to its initial position. This frees the terminal nails from the projections 50 and causes the entire series in the forward 80 set to descend, and be caught by the projections 44. In each upward movement of the rod, a pawl 68, pivoted upon the journals of the roll 58, engages a tooth in a ratchet-wheel 70 rotatable upon the bracket 43, and 85 turns this wheel through an angle which will depend upon the number of nails constituting each series in the holder-passages. Thus the loads of nails are counted, and a setting of the ratchet-wheel given for the delivery 90 of each load from the magazine-tubes under the control of the detent 46. Upon the reverse or downward stroke of the rod 59, a spring 72, which holds the pawl normally in 95 its working position, permits this to yield, so no effect is produced upon the ratchet-wheel. Rotatable with the ratchet-wheel is a cam-projection 74, which, after all the nails have been discharged from a set of the holder-passages and the ratchet-wheel has consequently completed 360 degrees of rotation, 100 contacts with a roll 76 upon the lever-arm 40 of the carriage-operating mechanism. The holder is thereby advanced to carry the now empty set of passages away from the plate-openings 20 and bring the succeeding set of 105 passages into delivering position.

Considering the holder to be full of nails and in its initial position with the first set of passages over the plate-openings 20, the bottom nails of the entire transverse set of series which is to supply the first load will be held between the walls of the upper extremities of the tubes 18 and the projections 44 of the detent 46. The operator, before 115 treadling the heelng machine, swings the loader-arm 22 from its co-operation with the die-block to its receiving position beneath the foot-plate of the mug. Here it elevates the rod 59 to oscillate the detent, thus 120 releasing a set of the nails from the passages by the retreat of the projections 44 from them, at the same time catching the succeeding nails of the series throughout the set by the projections 50. The rod at the 125

same time, through the pawl 68, turns the ratchet-wheel 70 to count the nail-delivery. The next movement of the loader to deliver to the die-block of the heeling machine allows the rod 59 to fall and the detent-projections 44 to come into position to retain nails released by the projections 50, thus restoring the system to normal. This continues until all the series of nails in the forward set have been delivered, at which time the cam 74, as a result of the complete rotation of the ratchet-wheel 70, will have reached the roll 76 of the carriage ratchet mechanism. By this, the carriage is advanced for one step, and the next set of nail-passages brought into delivering relation with the plate-openings, where they are held by the detent-projections 44. This operation may go on until the series of nails in all the sets have been used, when the empty holder will be removed and a fresh one filled with nails substituted. It should be observed that by this apparatus, not only is the operator's burden in shifting the nail-holding devices greatly reduced, but the cost of production of these devices, considering their capacity, is also substantially decreased. With the nail-holding block of Patent No. 1,325,751, the cost of drilling the openings, each of which contains but a single nail, is considerable. With my holder, but two plates at the top and bottom require to be drilled for the reception of twelve nails in a passage.

Having described my invention, what I claim as new and desire to secure by Letters Patent of the United States is:

1. A supplying apparatus comprising means for holding a plurality of series of fastenings arranged in sets, means for delivering individual fastenings from each of the series of a set, means arranged to count the deliveries, and means controlled by the counting means for preparing another set for delivery.

2. A supplying apparatus comprising a holding member having openings arranged in sets and each adapted to contain a series of fastenings, means arranged to control the successive delivery of fastenings from all the series of a set, and means acting upon the completion of delivery from said set for bringing another set into delivering position.

3. A supplying apparatus comprising a holding member arranged to contain a plurality of series of nails arranged in a set, means arranged to control simultaneously from all the series of a set the successive delivery of nails one by one from each series, and means acting upon the completion of delivery from the set for bringing another set into delivering position.

4. A supplying apparatus comprising a holding member arranged to contain a plu-

rality of series of nails, each series consisting of nails standing end upon end, controlling means arranged to permit the successive descent of nails in a series, and means governed with the controlling means for bringing another series into cooperation with the controlling means.

5. A supplying apparatus comprising a holding member arranged to contain a plurality of vertical series of nails, a supporting member upon which the holding member travels bodily in a horizontal direction, nail-controlling means associated with the supporting member, and means for moving the holding member upon the supporting member to bring different series into cooperation with the controlling means.

6. A supplying apparatus comprising tubes, a member having nail-holding passages movable into alinement with the tubes, and means associated with the tubes for controlling the delivery of nails from the passages to said tubes.

7. A supplying apparatus comprising tubes, a member having nail-holding passages movable into alinement with the tubes, and an oscillatory controlling member movable through the walls of the tubes into engagement with the nails.

8. In a nail-supplying apparatus, a movable holder having a passage arranged to contain nails in a vertical series, a delivery-controlling member provided with portions alternately contacting with terminal nails of the series, and means arranged to govern the movement of the holder during the control of delivery.

9. In a nail-supplying apparatus, a traveling holder having a passage arranged to contain nails in a vertical series, an oscillatory detent provided with spaced projections arranged to alternately retain and release terminal nails of the series, and connections to the detent arranged to govern the holder in its travel.

10. In a nail-supplying apparatus, a holder having a set of passages each arranged to contain a series of nails, and a movable delivery-controlling member common to all the series of a set and having nail-engaging projections corresponding to each series.

11. A nail-supplying apparatus comprising a plurality of tubes each provided with an opening in a portion of its wall fixed against movement, an oscillatory member having spaced projections movable into the tubes, and a traveling device provided with nail-holding passages movable into alinement with the tubes.

12. A nail-supplying apparatus comprising a plurality of tubes each provided with an opening in its wall, an oscillatory member having spaced projections movable into the tubes, and a device provided with sets

of nail-holding passages movable into alignment with the tubes.

13. A nail-supplying apparatus comprising a plate provided with a series of openings, a carriage movable over the plate and having passages each arranged to contain a series of nails, and means for moving the carriage to bring different passages into alignment with the openings and for controlling the successive delivery of nails from the passages.

14. A nail-supplying apparatus comprising a plate provided with a series of openings, a carriage movable over the plate and having passages each arranged to contain a series of nails, means for moving the carriage step by step to bring different sets of passages into alignment with the openings, nail-tubes depending from the openings, and a nail-controlling member movable through the sides of the tubes.

15. The combination with a traveling holder arranged to contain fastenings in a series resting one upon another, of means fixed relatively to the travel of the holder for controlling the delivery of fastenings from the holder, and a device movable to transfer fastenings delivered from the holder and arranged to actuate the controlling means.

16. A supplying apparatus comprising a holder arranged to contain a plurality of fastenings in a vertical series, means arranged to control the successive delivery of the lowermost fastenings one by one from a series, means acting upon the completion of delivery from said series for bringing another series into delivering position, and a device movable to transfer fastenings delivered from the holder and arranged to actuate both of said means.

17. The combination with a traveling holder arranged to contain nails in a vertical series, of a retaining member arranged to oscillate about a fixed point into engagement with successive nails of the series, and a movable nail-loader arranged to actuate the retaining member.

18. The combination with a movable holding device arranged to contain a plurality of series of nails, of a retaining member movable into engagement with successive nails of the series, a mechanism for moving the holding device to bring successive series of nails into co-operation with the retaining member, and a movable device arranged to both actuate the retaining member and the holder-moving mechanism.

19. The combination with a movable holding device arranged to contain a plurality of series of nails, of a retaining member movable into engagement with successive nails of the series, a mechanism for moving the holding device to bring successive series of nails to a delivering point, and a nail-loader

movable to the delivering point and arranged to successively actuate the retaining member and the holder-moving mechanism.

20. The combination with a movable device having a plurality of nail-holding passages, of a member movable to control the simultaneous delivery of nails from a plurality of the passages, mechanism for moving the holding device to bring passages successively into co-operation with the controlling member, and a movable nail-transferring device arranged to actuate the controlling member for each transferring movement and to actuate the moving mechanism after a plurality of such movements.

21. The combination with a plate provided with a series of openings, of a carriage movable over the plate and having passages arranged to receive series of nails, an oscillatory detent associated with the openings, a ratchet mechanism for moving the carriage to bring sets of passages into alignment with the openings, and means common to both for oscillating the detent and actuating the ratchet mechanism.

22. The combination with a plate provided with a series of openings, of a carriage movable over the plate and having passages arranged to receive series of nails, an oscillatory detent associated with the openings, a ratchet mechanism for moving the carriage to bring sets of passages into alignment with the openings, and a nail-loader movable into receiving position beneath the openings and arranged to there act upon both the detent and ratchet mechanism.

23. The combination with a plate provided with a series of openings, of a carriage movable over the plate and having passages arranged to receive series of nails, an oscillatory detent associated with the openings, a ratchet mechanism for moving the carriage to bring sets of passages into alignment with the openings, a member connected to the detent, a contact member movable by said detent member and acting upon the ratchet mechanism, and a nail-loader movable into contact with the detent member.

24. The combination with a plate provided with a series of openings, of a carriage movable over the plate and having passages arranged to receive series of nails, an oscillatory detent associated with the openings, a ratchet mechanism for moving the carriage to bring sets of passages into alignment with the openings, a reciprocal member connected to the detent, a pawl carried by said member, a ratchet-wheel rotatable by the pawl, and a cam turning with the ratchet-wheel and acting upon the ratchet mechanism.

25. In a nail-supplying apparatus, a nail-holder comprising top and bottom plates spaced from each other and having successive sets of aligned pairs of openings, and

tubes secured in the pairs of openings and each arranged to contain a series of nails.

26. A supplying apparatus comprising a movable holder arranged to contain a plurality of vertical series of fastenings, means arranged to control the successive delivery of the lowermost fastenings one by one from a series, and connections to the controlling means arranged to bring another series into 10 delivering position.

27. A supplying apparatus comprising a

movable holder arranged to contain a plurality of vertical series of fastenings, means arranged to control the successive delivery of the lowermost fastenings one by one from 15 a series, and a device movable to transfer fastenings delivered from the holder and arranged to actuate the controlling means and to govern the movement of the holder.

In testimony whereof I have signed my 20
named to this specification.

ELMER R. POPE.
